COIN CONTROLLED DISPENSER

Ralph R. Quintrell, Etowah, Tenn.

Application May 11, 1940, Serial No. 334,595

7 Claims. (Cl. 312—35)

My invention relates to improvements in coin controlled manually operated dispenser, and the primary object of my invention is to provide a simple, inexpensive and practical arrangement of this character which is especially adapted to the vending of small articles of merchandise on a profit-sharing basis.

Other important objects and advantages of my invention will be apparent from a reading of the following description and the appended drawings wherein a preferred embodiment of my invention is shown for illustrative purposes.

In the drawings:

Figure 1 is a side elevational view showing incorporation of the invention in a small counter size form.

Figure 2 is a front elevational view thereof.

Figure 3 is an enlarged top plan view with the top of the casing removed and with the moving parts in initial inoperative positions.

Figure 4 is a transverse vertical sectional view taken through Figure 3 approximately on the line 4—4 of Figure 3 and looking upwardly in the direction of the arrows.

Figure 5 is a fragmentary transverse vertical sectional view taken through Figure 3 approximately on the line 5—5 and looking upwardly in the direction of the arrows.

Figure 6 is a fragmentary horizontal sectional view taken through Figure 5 approximately on the line 6—6 and looking downwardly on the direction of the arrows.

Referring in detail to the drawings, the numeral 5 generally designates a sheet metal casing of vertically elongated rectangular form having a suitable base 6 for resting on a merchandise counter or other suitable support (not shown). A removable top 7 rests upon and is hinged at 8 on the open upper end of the casing and has lockable retention means 9 thereon.

Substantially midway between the top and bottom of the casing angle brackets 10 and 11, respectively, are secured to the opposite side walls of the casing to support the mechanism base 13 which has an upstanding integral flange 14 on its front end through which bolts 15 traversing the front wall 16 of the casing and the coin slot frame 17, pass to secure these parts in stationary vertically supporting relation. The mechanism base 13 and its flange 14 are preferably of relatively heavy metal so as to lend sufficient rigidity to the device to permit of using a light weight inexpensive casing 5 without undue sacrifice of serviceability.

An L-shaped bracket 48 is secured to depend

from the left hand side of the mechanism base and has a declining portion 19 fastened to the underside of the upper part of a forwardly declining merchandise chute 20 which is additionally secured at 21 to the adjacent left side wall of the casing to empty into the cup-shaped receiver 22 which is mounted on the casing front wall partly within the access opening 23.

The upper end of the chute 20 is positioned directly under the lower end of the vertical tubular conduit 24 which passes upwardly through one of a number of openings in the open work mechanism base 13. A sleeve 25 may be telescopically secured on the lower end of the conduit 24 to provide for a "jack-pot" accumulation of merchandise in the tube 24, such as small tins of aspirin or the like, above the gate 26 which is pivoted on a horizontal axis and equipped with an adjustable weight 27 to predetermine the number of pieces which must accumulate in the tube 24 to effect the dropping of the gate and the delivery of all of the accumulated articles to the customer via the chute 20 and receiver 22.

The upper end of the tube 24 extends through the base plate 28 of the vertical merchandise container tube 29 which has its lower end fixed in an opening formed in a top plate 30 at a point adjacent to the rear of the tube 24. The top plate 30 is spaced upwardly from the base plate 28 by spacing means 31, securing means 32 acting to hold the parts together. The articles or pieces to be dispensed are stacked like coins in the tube 29 with the lowermost pieces resting on the top of the base 28. A horizontally swingable transfer element 33 is journaled on a vertical pivot 34 on the base, the transfer element being hook-shaped in plan as shown in Figure 6 of the drawings. The vertical pivot 34 traverses the smaller end of the transfer element 33 and is located on the base plate 28 to the left of the tube 29 with the transfer element extending around behind the said tube with its wider end positioned to the right of the said tube. The transfer element 33 is normally retracted by the spring 35 to a slightly rearwardly angulated position with the heel 36 presented at an acute angle for cam arrangement by pins 37 depending from the toothed wheel 38 as the wheel 38 rotates in a counter-clockwise direction. The pins 37 cam the element 33 so as to swing the element 33 on its pivot 34 and cause its curved front edge 39 to push the bottom-most one of the articles stacked in the tube 29 out of the tube and along the plate 28 to the upper end of the tube 24, through which the transferred article then falls. As each pin 37

moves off the end of the heel of the transfer element 33, the spring 35, which is stretched between the transfer element and a point on the base 13, returns the transfer element to initial position.

The toothed wheel 38 has a depending hub 40 which spaces it upwardly from the mechanism base 13, the hub 40 being journaled on the spindle 41 which rises from the base 13. In a profit-sharing arrangement of the device the pins 31 will be circumferentially spaced on the wheel 38 at such intervals as to cause operation of the transfer element 33 to dispense an amount of merchandise of a predetermined value in excess of the value of the coins or tokens used to operate the coin slides to be described. The circumferential teeth 42 on the wheel 38 are of a size and spacing such that the wheel will be advanced in a counter-clockwise direction a predetermined number of teeth according to which of the coin slides is operated.

Pivoted intermediate its ends on the spindle 41 above the toothed wheel 38 is the irregularly shaped cam plate 43 which is held down in place by the head 44 on the upper end of the spindle 41 and a washer 45 under said head. One end of the cam plate has a contractile spring 46 stretched between it and an anchor 47 on a forward part of the mechanism base 13. A bell-crank pawl 48 is pivoted to the underside of the same end of the cam plate 43 and has its nose engaging the teeth 42 of the wheel 38 and its remaining end connected with a contractile spring 49 which is also connected to a rearwardly positioned anchor 50 on the cam plate. A bell-crank dog 51 is pivotally mounted on the base 13 forwardly of the cam plate and has one arm engaging the teeth of the wheel 38 and has its remaining arm connected to one end of a contractile spring 52 whose opposite end is anchored to a bracket 53. By reason of these arrangements, rocking of the left hand end of the cam plate 43 in a forward direction, such as is produced by operation of the coin slides, will swing the right hand end of the cam plate rearwardly with the pawl 48 in engagement with the teeth on the wheel 38, thereby turning the wheel in a counter-clockwise direction. At the same time that the wheel turns the dog 51 trips over the teeth 42 but comes to rest between two of the teeth when the movement ceases, in a manner to positively prevent reverse or clockwise rotation of the wheel 38.

The cam plate 43 has, in the present embodiment, three vertically projecting cams 54, 55, and 56, respectively, spaced along the cam plate from left to right, and aligned in rear of the related conventional type coin slides 57, 58, and 59, respectively, which are mounted by the frame 17 on the front wall of the casing.

The slide 60 of the coin slide 57 has a long 60 slightly angulated cam face 61 to engage the cam 54. The cam face 62 on the slide 63 of the coin slide 58 is shorter, rounded, and more acutely angulated, to engage the cam 55, while the cam face 64 of the slide 65 of the coin slide 59 is squared to engage the cam 56. As is evident from Figure 3 of the drawings the coin slides are graduated in capacity from left to right to accept larger coins or tokens and the corresponding coin slides and coins are arranged to turn the wheel 38 a correspondingly greater number of teeth, when the coin slides are pushed in with a proper coin or token in place therein. It will be observed that the mechanism of the device is easily accessible in the casing or may be easily 75

removed from the casing for repair, adjustment, or replacement.

Although I have shown and described herein a preferred embodiment of my invention, it is to be understood that I do not wish to limit the application to the precise structural details disclosed, except as may be required by the scope of the subjoined claims.

Having described the invention, what is claimed as new is:

1. A coin controlled dispensing device of the character described, said device comprising a support, a mechanism base plate mounted on an elevated part of said support, an article dispensing container on said support, dispensing means including transfer means for moving the lowermost article of a stack of the articles from the bottom of said container, a rotary toothed wheel on said base plate, said wheel having an abutment to engage and operate said transfer means when sufficiently turned in one direction, means to prevent rotation of said wheel in the opposite direction, a rocker on said support, a pawl on said rocker engaging the teeth of the wheel, a plurality of cams on said rocker, and a similar plurality of selectively operable slides on said support each having a manually operable element, said slides having portions positioned to operatively engage the individual cams to which they relate, to rock said rocker to effect rotation of said wheel for a corresponding circumferential distance.

2. A device in accordance with claim 1 wherein said dispensing means comprises a chamber into which the transferred article falls, a depressible gate closing the lower end of said chamber to cause accumulation of the transferred articles in said chamber until the weight of the accumulated articles overcomes the resistance of said gate, and receiving means to receive the articles discharged from said chamber.

3. A coin controlled article dispensing device, said device comprising a support, a mechanism base mounted on said support, a vertical article container on a part of said base with its lower end sufficiently spaced from the top of said base to permit the lowermost article to rest on said part of the base and be clear of the lower end of the container, a discharge conduit opening through said part of the base at one side of said container, a transfer element pivoted on a vertical axis on said part of the base at one side of said container, said transfer element being swingable to engage and transfer said lowermost article from the lower end of said container into the upper end of said discharge conduit, and coin controlled means for operating said transfer element.

4. A coin controlled article dispensing device according to claim 3 wherein said transfer element is pivoted adjacent one end thereof and has retracting spring means to swing said transfer element to initial position after operation.

5. A coin controlled article dispensing device according to claim 3 wherein said transfer element is pivoted adjacent one end thereof and has retracting spring means to swing said transfer element to initial position after operation; said transfer element being formed with a cam lobe on the end thereof opposite the pivot location and said coin controlled means comprising a mechanism comprising at least one member engageable with said lobe to operate said transfer element.

6. A coin controlled article dispensing device

according to claim 3 wherein said transfer element is pivoted adjacent one end thereof and has retracting spring means to swing said transfer element to initial position after operation; said transfer element being formed with a cam lobe and said coin controlled means comprising a mechanism comprising at least one member engageable with said lobe to operate said transfer element; said coin controlled means comprising a plurality of horizontal slides on said support and projecting along said mechanism base, a toothed wheel rotatably mounted on a vertical axis on said base, said member projecting from said toothed wheel, a rocker mounted on a vertical axis on said base, a spring pressed operating pawl carried by said rocker in operative engagement with the teeth of said wheel to rotate said wheel in one direction only, a plurality of cams on said rocker corresponding in number and position to the said plurality of horizontal slides, said slides and the related cams being formed to rock said rocker to operate said wheel different predetermined portions of a revolution of the wheel when one of the slides is operated into engagement with its companion cam.

7. An article dispensing device comprising a casing having a plurality of different coin operated slides mounted thereon on a wall thereof, each such slide comprising a horizontal part adapted to project inwardly from the said wall when operated, a mechanism base plate mounted in said casing below the horizontal parts of the coin slides, said base having an elevated portion at one side thereof formed with a first vertical opening, a vertical article container on said elevated portion with the lower end communicating

with said vertical opening, said base plate having a portion on which the lowermost article rests, a dispensing conduit depending from said elevated portion of the base with its upper end communicating with a second vertical opening formed in said base plate and in said elevated portion and spaced from one side of said first vertical opening, a spring retracted transfer element pivoted on a vertical axis on said elevated portion, said transfer element being arranged to swing from inoperative position and across said first vertical opening below the lower end of said vertical article container to push the lowermost article into said second vertical opening to fall into said dispensing conduit, said transfer element including a cam lobe, a toothed wheel rotatably mounted on a vertical axis on the top of said base, said wheel having circumferentially spaced legs depending therefrom for operatively engaging the cam lobe of said transfer element, a rocker above and pivoted on the same axis as said toothed wheel and extending transversely across said wheel, a spring operated pawl carried by said rocker in operative engagement with the teeth of said wheel to turn the wheel in one direction only as said rocker is operated, spring means retracting said rocker to disengage said pawl from the teeth of said wheel, said rocker having transversely spaced cams projecting upwardly therefrom, said cams corresponding in number and position with said horizontal parts of the slides, said horizontal parts and said cams being arranged to engage and produce rocking of said rocker to advance said wheel a predetermined amount according to the slide operated.

RALPH R. QUINTRELL.
